UNITED STATES PATENT OFFICE

151,308

DESIGN FOR AN ELECTRIC MOTOR

Theodore R. Wieseman and Russell I. Robinson,
Milwaukee, Wis., assignors to The Louis Allis
Company, Milwaukee, Wis., a corporation of
Wisconsin

Application October 17, 1947, Serial No. 141,964

Term of patent 14 years

(Cl. D26—5)

To all whom it may concern:

Be it known that we, Theodore R. Wieseman and Russell I. Robinson, citizens of the United States, residing at Milwaukee, in the county of Milwaukee and State of Wisconsin, have invented a new, original, and ornamental Design for an Electric Motor, of which the following is a specification, reference being had to the accompanying drawing, forming part thereof.

Figure 1 is a perspective view of an electric motor, embodying our new design;

Figure 2 is an end view of the motor illustrating that end thereof not shown in Figure 1;

Figure 3 is a side elevational view of the motor showing that side thereof not shown in Figure 1.

The dominant features of our design reside in those portions illustrated in full lines.

We claim:

The ornamental design for an electric motor, as shown and described.

THEODORE R. WIESEMAN.
RUSSELL I. ROBINSON.
